UNITED STATES PATENT OFFICE.

DAVID B. WHISTLER, OF DAYTON, OHIO.

WINDOW.

Application filed October 15, 1925. Serial No. 62,515.

This invention relates to improvements throughout to suit the adaptation of the invention thereto.

The objects attained in the window consist of a window of the double-hung, counter-balanced type, in which both sash are adapted for both vertical and angular adjustments, which is effectually weathered without the addition of weather stripping, which cannot rattle when closed, which cannot be forced open from outside, which acts to prevent direct draughts through the window and to exclude the weather as adjusted for ventilating, which is accessible for cleaning outside the sash without removing the screen or getting outside the window, which has architectural distinctiveness and, with all, is of simple, low cost construction.

The particular novelty of the improved window as herein set forth consists in improvements in the hollow metal moldings which are a feature of the invention, in means provided for latching the sash in various positions of adjustment, in means for assembling the meeting rail moldings on the lower sash and in an improved meeting rail drip strip.

The improvements comprised in the invention are adaptable for both wood and metal windows, or a combination of wood frames and metal sash. For the purpose of illustrating the invention the same is shown in the accompanying drawings as applied to a wood window.

In the drawings:

35 Figs. 1, 2, 3, 4 and 5 are vertical sectional views of the window illustrating various positions of adjustment;

40 Fig. 6 is a detail view of the lower sash and jamb construction;

Fig. 7 is a detail view taken on line 7-7 of Fig. 6;

Fig. 8 is a detail view taken on line 8-8 of Fig. 5;

45 Figs. 9, 10 and 11 are detail views of the meeting rail moldings;

Fig. 12 is a detail view of a modified construction including a buffer and extra weathering for the lower sash.

50 As here shown the window consists of the usual parts of wood window construction consisting of the opposite side jambs 1, head jamb 2, sill 3, stool 4, apron 5, trim 6, outer casing 7, upper sash 8, lower sash 9, sash weights 10 and sash cables 11, cable connections 11^a, the construction being modified

in the invention consist in the meeting rail outer moulding 14, meeting rail inner mouldings 15 and 16, upper sash latching bead 17, lower sash latching beads 18, lower jamb guide plate 19, lower sash guides 20 and 21, meeting rail drip strip 22 and upper sash latch 23. Associated with the parts in various relations modified by the invention are the opposite side jamb mouldings 12, head jamb molding 13, latching bars 24, latching knob 25 and latch plates 26 secured to the opposite jambs.

In Figs. 1 and 5 the window is shown closed. The effective weathering of the window at the head, meeting rails and sill is here shown as indicated at *a*, *b* and *c*, the weathering along the side jambs being better shown in Fig. 8. The weathering is effected by the outward pressure exerted on both sash by the latch bars 24 as the same are projected outwardly by means of the knob 25 into engagement with the latch plates 26, the inner faces of the engaging ends of the bars being tapered which serves to give a wedging action to the bars as they engage the plates and thus to force the sash outwardly into contact under pressure with the sash stops 1^a secured to the jambs, the upper sash being pressed outwardly by the force exerted thereon by the lower sash at the meeting rails. At the sill the movement of the lower sash is inward against the edge of the stool 4 as a result of the pivotal connection of the lower sash with the terminal ends 28 of slots 27 of the opposite sash guide plates 19. At the meeting rails the lower sash engages the yieldable drip strip 22, the upper edge of which, as here shown, is extended upward under the putty or the lower edge of the glass, being thus effective to prevent moisture penetrating between the drip strip and sash rail.

It will be observed from the foregoing description and more particularly from the drawings that both sash along the entire weather line are in firm contact under pressure with coactive structural features between the sash and of the jambs and sill, that this tight fitting relation which is effective to exclude dust, soot, etc., as well as draughts and elements of the weather, results upon the normal closing of the window regardless of

the degree of loose or free fitting the sash may have when the latch bars are released, the taper of the latch bars at their engaging ends being sufficient to insure the contact under pressure on the weather line as the window is closed. Obviously upon releasing of the latch bars both sash are free and can be operated without the common fault of sticking of double-hung windows of ordinary construction.

Fig. 2 illustrates the lower sash adjusted at an angle and latched in the jambs, and the upper sash partially lowered and latched with a jamb molding, the positions illustrating selective positions of the sash for ventilating. It will be observed that currents of air entering the window over the lower sash will be deflected upward, direct draughts through the lower opening being thus avoided. The lower sash in this position will also act in large measure to exclude weather and thus to protect floors and furnishings during storms. The sash is also securely interlocked with the jambs and cannot be forced open from outside, the upper sash being also adapted to be latched fully closed or in a selected position by means of the latch 23 which as here shown is supported on one of the jamb moldings 12 and is adapted to engage the notches 17^a of one of the latching beads 17 which are secured to the side rails of the upper sash.

In Fig. 3 the upper sash is illustrated in fully closed position and the lower sash in fully open vertical position. The manner of latching the lower sash in a selected position by means of the latch bars 24 and latching beads 18 is here shown, the bead portion 18^a acting as a retaining guide for the sash in its vertical movements. The figure also serves to illustrate the relation of the sash to the sash guides 20 and the relation of the guides to the jamb guide plates 19, the structural features of these parts being more clearly shown in Figs. 7 and 8, Fig. 8 also showing in cross section the relation of sash guides 21 to guides 20, the former being flanged linear beads secured to the opposite side edges of the sash in a manner to adapt the guides 20 to coact therewith telescopically and slidably, guides 20 having their lower ends connected slidably in the slots of the jamb guide plates 19 by means of a pivot stud 19^a, clearance being cut out of the jamb back of the plate for a retaining head 20^a of stud 19^a as shown in detail Fig. 7.

It will be observed from the foregoing detailed description that the guides 20 move with the lower sash in the angular adjustments thereof, and remain stationary, except inward movement with the sash over the face of the jambs to move the sash out of the plane of the upper sash, when the lower sash is adjusted vertically. The slight inclination of slots 27 in plates 19 tend to ease operation of

the sash as the same is lowered and moved laterally to closed position.

In Fig. 4 both sash are shown lowered and turned inward at an angle. This is the position of the sash for cleaning, the sash being lowered one at a time, the limit of the angular adjustment being 90 degrees, thus making possible full open windows when desired. In this figure also the relation of the sash to the window screen *d* is illustrated, it being observed that the movement of the sash in all relations is within the plane of the screen.

In Fig. 5 and detail Figs. 9, 10 and 11 the improved meeting rail construction is illustrated. Parts 15 and 16 are secured to the sash rail, part 15 at the center and parts 16 adjacent the opposite edges of the sash, thus the parts are adaptable to any width of sash. Part 15 is provided with opposite guides 15^a for the off-set inner ends of the latch bars 85 spaced one from the other to receive the pinion 25^a of the latching knob 25 which engages racks 24^a formed in the latch bars. Parts 16 are each provided adjacent their outer ends with guides 16^a for the latch bars and with end portions 16^b adapted to be turned upward to close the ends of the outer molding 14 which is adapted to be applied telescopically to parts 15 and 16 as the moldings are assembled on the sash.

A suitable modification of the lower sash guides 20-21 is illustrated in detail Fig. 12, to adapt the modified guides 20^b-21^b to have a weathering element 29 associated therewith, the weathering consisting preferably of yieldable material, as felt or rubber, supported in the guide 20^b interposed between the guide and the adjacent jamb and having the double function of a weathering and a buffer for the sash. In both forms of construction the guides 20-20^b serve to add a finishing bead along the inner side edges of the lower sash.

Having described my invention, I claim:

1. A window including in combination with the frame, a sash operable vertically and angularly relative to said frame, a guide for the sash interposed between an edge thereof and the adjacent jamb of said frame, pivoted near its lower end on said jamb and connected slidably with said sash.

2. A window including in combination with the frame, a sash operable vertically and angularly relative to said frame and having a bead secured to a vertical edge thereof, a guide for the sash interposed between said edge and the adjacent jamb of said frame, pivoted on said jamb and operable slidably relative to said bead.

3. A window including in combination with the frame, a sash operable vertically and angularly relative to said frame and having a bead secured to a vertical edge thereof, a guide for the sash arranged telescopically of said bead and interposed be-

- between said edge and the adjacent jamb of said frame, the guide being pivoted on the jamb and operable slidably relative to said bead as the sash is adjusted vertically and 5 operable with the sash as the sash is adjusted angularly.
4. A window including in combination with the frame, a sash adjustable laterally, vertically and angularly relative to said 10 frame, a guide for the sash connected slidably thereto and interposed between an edge thereof and the adjacent jamb of said frame, the guide being operable with the sash in said lateral and pivotal adjustments thereof.
- 15 5. A window including in combination with the frame, a sash adjustable laterally, vertically and angularly relative to said frame, a plate secured to a jamb of the frame adjacent its lower end and having a slot extended transversely of the jamb, a guide for the sash connected slidably thereto and interposed between an edge of the sash and said jamb, the guide being pivoted on said plate, slidably in said slot and operable with 20 the sash in said lateral and angular adjustments thereof.
6. A window including in combination with the frame, a sash adjustable laterally, vertically and angularly relative to said 25 frame, a plate secured to a jamb of the frame adjacent its lower end and having a slot extended transversely of the jamb and a terminal of the slot extended downwardly, a guide for the sash connected slidably there- 30 to and interposed between an edge of the sash and said jamb, the guide being normally pivoted in said terminal, slidable in said slot and adapted to move with the sash in said lateral and angular adjustments 35 thereof.
- 40 7. A window including in combination with the frame, a sash adjustable vertically and angularly relative to said frame, weatherbeads for the sash secured to the side 45 jambs of said frame and a shoulder of the window stool acting as an inner stop for the sash, means to pivot the sash on the jambs of said frame adjacent the lower ends thereof, means to guide the lower edge of the 50 sash over the inner edge of the stool as the sash is lowered and disposed angularly, and latching means carried by the sash and engageable with the jambs acting to force the sash above its pivot center outward into pressure contact with the weatherbeads for the sash and below the pivot center inward into pressure contact with the stool.
- 55 8. A window including in combination with a window frame, upper and lower sash, the lower sash being adjustable vertically and angularly relative to said frame, weathering for the sash secured to the side jambs of the frame, a weathering disposed over the junction between the sash, and a shoulder 60 extended above the window sill acting as an inner stop for the sash, means to pivot the sash on the jambs of said frame adjacent the lower ends thereof, means to guide the lower edge of the sash over the inner edge of the stool as the sash is lowered and disposed angularly, and latching means carried by the sash and engageable with the jambs acting to force the sash above its pivot center outward into pressure contact with the weathering and below the pivot center inward into pressure contact with the shoulder.
- 65 9. A window including in combination with a window frame, upper and lower sash, the lower sash being adjustable vertically and angularly relative to said frame, weathering for the sash along the side and head jambs of the frame and over the juncture between the sash and a shoulder extended above the window sill inside the sash, means to pivot the sash on the jambs of said frame adjacent the lower ends thereof, means to guide the lower edge of the sash over the inner edge of the stool as the sash is lowered and disposed angularly, and latching means carried by the sash and engageable with the jambs acting to force the sash above its pivot center outward into pressure contact with the weathering and below the pivot center inward into pressure contact with the shoulder.
- 70 10. A window comprising vertically aligned sash, a weathering for the sash consisting of a strip extended transversely of the window, overlapping the meeting rail joint between the sash and having its upper edge extended under the upper sash glazing.
- 75 11. A window comprising vertically aligned sash, a weathering for the sash consisting of a flexible strip secured to the upper sash, extending transversely of the window, overlapping the meeting rail joint and yieldable to the outward pressure of the lower sash.
- 80 12. A window including in combination with upper and lower sash, a moulding of the lower sash meeting rail extended upward over the lower meeting rail of the upper sash and comprising a part secured to the lower sash meeting rail, and a finishing moulding applied telescopically to said part.
- 85 13. A window including in combination with upper and lower sash, a moulding of the lower sash meeting rail extended upward over the lower meeting rail of the upper sash and comprising a plurality of parts adapted to be spaced one from another according to the width of the sash and a finishing moulding applied telescopically to said parts.
- 90 14. A window including in combination with upper and lower sash, a moulding of the lower sash meeting rail extended upward over the lower meeting rail of the upper sash and comprising a part adapted to be secured to the meeting rail of the lower sash and a finishing moulding adapted to be applied
- 95 100 105 110 115 120 125 130

telescopically to said part after the same has been mounted on the sash.

15. A window including in combination with a frame, an upper sash operable vertically and a lower sash operable vertically and angularly relative to said frame, means to latch the lower sash with the frame in said angular relation therewith, and means to latch the upper sash in a position of vertical adjustment when the lower sash is in said position of angular adjustment.

16. A window including in combination with a frame, an upper sash operable vertically and a lower sash operable vertically and angularly relative to said frame, means to latch the lower sash with the frame in said angular relation therewith, and means fixed relative to the frame and adapted to coact with means supported on the upper sash to latch said sash in a selected position of vertical adjustment when the lower sash is in said position of angular adjustment.

17. A window including in combination with a frame, an upper and a lower vertically aligned sash supported in said frame, guides for the lower sash secured to the lower portions and extended transversely of said frame, guides for said sash interposed between the side edges of the sash and said frame, connected slidably to the sash and slidably and pivotally to the transverse guides whereby to adapt the lower sash to be adjusted relative to the upper sash.

18. A window including in combination

with the frame, a sash operable vertically and angularly relative to said frame, a guide for the sash interposed between an edge thereof and said frame and connected slidably to the sash, and a weathering and buffing element secured to said guides.

19. A window including in combination with a frame, a sash operable vertically and angularly relative to said frame, guides for the sash pivoted on the frame, interposed between the side edges of the sash and the frame, connected slidably to the sash and serving to form finishing beads along the inner side edges thereof.

20. A window including in combination with the frame, a sash operable in said frame, guides interposed between the sash and frame, connected slidably to the sash, and pivotally with the sash to the frame.

21. A window including in combination with the frame, a sash operable in said frame, guides interposed between the sash and frame, connected slidably to the sash, and pivotally and slidably with the sash to the frame.

22. A window including in combination with the frame, a sash operable in said frame, guides interposed between the sash and frame, connected slidably to the sash, and pivotally with the sash to the frame, and a weathering element interposed between said guides and the frame.

In testimony whereof, I affix my signature.
DAVID B. WHISTLER.
